MOUNTING FOR ORNAMENTAL ARTICLES

Frank M. Kane, Providence, R. I.

Application April 20, 1932. Serial No. 606,374

7 Claims. (Cl. 41—10)

This invention relates to the manufacture of ornamental articles such as pendants or the like for use with chains, necklaces, earrings, brooches and other articles of jewelry or adornment.

- 5 The invention is particularly concerned with an improved method of fabricating articles of the type specified by mounting pearls, beads, faceted stones or brilliants and other similar objects in groups or clusters.
- 10 One object of the invention is to provide in an article of the type specified a simple and inexpensive mounting for drilled beads, pearls or faceted brilliants whereby to provide a pendant or ornament for application to articles of jewelry or for 15 ornamenting millinery.

Another object of the invention is to provide a mounting for the beads or other objects which may be readily assembled in permanent form without the use of solder or extraneous connecting means.

20 Another object of the invention is to provide an article of the type specified wherein the mechanical mounting means are concealed from view by the pearls, beads or the like grouped in close association.

Another object of the invention is to provide an article of the type specified which is more ornamental and pleasing in appearance besides being less liable to disintegration or distortion in use.

25 Further objects of the improvement are set forth in the following specification which describes a preferred embodiment of the invention and one modification in the construction thereof as illustrated by the accompanying drawing. In 30 the drawing:

Fig. 1 is a view of the article constructed in the form of a cluster of beads or pearls simulating the appearance of a bunch of grapes;

35 Fig. 2 is an enlarged sectional view of the same showing the method of mounting the beads or ornamental objects in the cluster;

Fig. 3 is a cross sectional view of the same taken on line 3—3 of Fig. 2;

40 Fig. 4 is a similar view showing a variation in the form of the objects grouped in the cluster as consisting of faceted brilliants;

Fig. 5 is a view similar to Fig. 1 showing a different arrangement of the beads or pearls in the cluster; and

45 Fig. 6 is a view showing the method of mounting the beads or pearls in accordance with the arrangement of the same illustrated in Fig. 5 of the drawing.

50 It is common in the jewelry and kindred arts to mount spherical, globular and faceted objects

such as beads, pearls, ornamental brilliants and the like in clusters whereby to provide pendants or charms for suspension from chains, necklaces, earrings, pins and the like. These clusters may have a general spherical shape or be of tapering 60 contour in simulation of an article of nature such as a bunch of grapes. The beads or other objects are usually fastened to a central wire or support having radial arms projecting therefrom and the present improved mounting differs from this 65 previously used form in that the beads or other objects are strung on a wire or wires encircling a central core or former shaped to the desired contour of the cluster.

Fig. 1 illustrates a plurality of objects such as 70 spherical beads or pearls grouped on the present improved mounting in the form of a cluster simulating a bunch of grapes and having means for attaching the same as a pendant to a chain or other support.

75 Fig. 2 shows a preferred form of construction of the mounting wherein is employed a central former or core 2 which in the present illustration of the invention is pear-shaped or, more properly, has the contour of a spinning top or plumb-bob. The former or core 2 may be constructed of any suitable material, preferably being molded from glass in order that it may not show through the transparent beads clustered therearound but have reflecting properties for 80 the surrounding objects. As illustrated in Fig. 2, the core 2 has a spherical top and a conical bottom portion terminating in a point. The core 2 is drilled axially at 3 to receive a central rod or wire 4 formed into a hook or ring 5 at its upper 85 end for attachment to the chain or other article from which it is to be suspended.

90 The axial wire 4 is extended beyond the lower point of the core 2 to adapt it to be impaled through the axial bore of a bead 6 or other similar object forming the lowermost element in the group or cluster. The lower end of the wire 4 is provided with a head or enlargement 8, or it may have applied thereto a relatively small bead which serves as a means for holding the lower 95 bead 6 in place. The other ornamental objects such as brilliants or beads 10 are assembled around the central core or former 2 by means of wires strung through their axial bores.

100 In the embodiment of the invention shown in Figs. 1, 2 and 3 the beads 10 are arranged in rows of diminishing number from top to bottom of the core 2. That is to say, the beads or objects 10 are strung on wires 11 in graduated number to form annular rows of the objects as illustrated 105 110

most clearly in Fig. 3. Starting at the bottom of the former 2 the first row of objects 10 will have the least number, being arranged to closely surround the projecting end of the wire 4 and resting on the lowermost bead 6. Another row of a greater number of beads strung on a wire 11 is arranged above the bottom row and so on with the uppermost row having the largest number of beads and surrounding that portion of the core 2 of greatest diameter. It will be understood that the beads 10 are strung onto their wires 11 before being assembled around the core 2, the ends of the wire in each ring being twisted together or otherwise fastened as indicated at 12 in Fig. 3.

To provide a finish for the top of the article or pendant a metal plate or ornamental device 13, shaped to concavo-convex form, is placed across the top of the core 2 to extend outwardly therebeyond above the uppermost row of beads 10. The plate or cap 13 is herein shown as being formed to simulate a spray of leaves radiating from the center of the cluster, but it is to be understood that the cap may be given any other ornamental configuration or design as desired. The plate or cap 13 is held in place against the top of the core 2 by inserting the axial wire 4 through a central hole therein before the end of the wire is bent into the hook or ring 5. With the beads strung on their circular wires 11 and assembled in close association about the central core 2 the forming of the hook or ring 5 serves to connect all the parts together in a substantially integral structure.

It will be observed that the present improved mounting provides for grouping the ornamental objects together without cementing the beads or brilliants to wires or the like and also without the use of solder or other extraneous means for joining the parts of the mounting. It is to be further noted that the present mounting provides for assembling the beads or other ornamental objects in a cluster with very little hand work and without requiring especial skill or expertness on the part of the workman. Thus, the invention provides for more rapid and economical fabrication of the pendant or ornament from conventional types of beads or other like objects whereby to reduce the cost of manufacture of the article in quantity.

Fig. 4 illustrates a ring or circlet of polygonally-shaped or faceted brilliants 15 strung on a supporting wire 11 surrounding the core 2, it being understood that the whole series grouped around the core may be made of this shape and, likewise, other objects of different shapes and forms may be used in similar arrangement.

Fig. 5 of the drawing illustrates a modified form of construction of the mounting for the beads, brilliants or other ornamental objects. In this embodiment of the invention all of the beads 16 with the exception of the lowermost one 17 are strung on a continuous wire 18 which is coiled about the central core 2 in a spiral or helix. The spiral wire 18 is shown in expanded condition in Fig. 6, while Fig. 5 illustrates the completed article with the beads compacted in close association. While with this form of construction the beads assume a more or less spiral arrangement around the central core 2, the general appearance of the pendant is practically the same as that first described as will be apparent from a comparison of Fig. 5 with Fig. 1. In the last described embodiment of the invention the lower end of the wire 18 may be secured on itself or to the

axial wire 2 and the opposite end attached in any suitable manner to another portion of the wire.

It will be observed from the foregoing that the present invention provides a particularly simple and ingenious means for assembling a plurality of ornamental objects such as beads or brilliants in a group or cluster while securing the same in place without danger of displacement thereof or disintegration of the whole. The improved mounting for the clustered objects lends itself to economical manufacture, being constructed principally of wire stock without preforming in tools or dies and being assembled by hand operations requiring little skill or expertness on the part of the workman.

While I have herein described and illustrated a preferred form of construction of the mounting and a preferred method of disposing the ornamental objects thereon, it is to be understood that modifications other than those mentioned may be made in the structure and arrangement of the parts without departing from the spirit or scope of the invention. Therefore, without limiting myself in this respect, I claim:

1. A pendant or like ornamental article comprising a central core of the general shape of the desired contour of the article, and ornamental objects strung on wire encircling the core in a plurality of loops to hold the objects in close association therewith.

2. An article of the type specified comprising a central core, and a plurality of ornamental objects in the form of beads strung on wire encircling the core in a plurality of coils and held at the end to group the objects in close association in the form of a cluster.

3. A pendant in the form of a cluster of ornamental objects comprising a central core shaped to the desired contour of the cluster, and series of ornamental objects in the nature of beads strung on wire encircling the core in a series of coils to hold the objects in contiguous relation to its sides and grouped thereabout in abutting relation to each other.

4. An article of the type specified comprising a central core of predetermined form, an axially arranged wire projecting from one end of the core, an object in the nature of a bead strung on the projecting end of the wire, and a series of rows of like objects strung on wire encircling the core in a plurality of coils to hold the objects in close association and contiguous to its sides.

5. An article of the type specified comprising a generally spherical core, a wire extending axially through said core, an ornamental object in the form of a bead held on the lower extremity of the axial wire, and rows of similar objects strung on a wire which encircles the central core in a plurality of coils to secure the objects in close association contiguous to the sides of the core in the form of a cluster.

6. An article of the type specified comprising a central core, a wire extending axially through the core and formed with an enlargement at one end and a ring at its opposite end, an ornament in the nature of a bead impaled on the projecting portion of the wire and held in place by the enlargement at its end, and series of similar ornaments strung on a wire which encircles the core in a series of coils to hold the ornaments in abutting relation to its sides and contiguous to each other.

7. In an article of the type specified, the combination of a central core, an axial wire projecting through said core with an enlargement at one end and a ring at its opposite end, a bead-like ornament strung on the projecting end of the wire, a series of similar ornaments strung on a wire encircling the core in spiral coils to hold the ornaments in abutting relation to its sides and in contiguous relation to each other, and a cap surmounting the top of the core and extending laterally therefrom to overlie the uppermost row of ornaments assembled thereon. 80
